UNITED STATES PATENT OFFICE.

J. FRANK WILCOMBE, OF WORCESTER, MASSACHUSETTS, ASSIGNEE, BY MESNE ASSIGNMENTS, TO HEMPHILL COMPANY, OF CENTRAL FALLS, RHODE ISLAND, A CORPORATION OF MASSACHUSETTS.

KNITTING MECHANISM.

Application filed June 20, 1919. Serial No. 305,473.

To all whom it may concern:

Be it known that I, J. FRANK WILCOMBE, a citizen of the United States, and resident of Worcester, Mass., have invented certain new and useful Improvements in Knitting Mechanisms, of which the following is a specification.

My invention is an improvement in knitting machine organizations in which a new form of knitting instrument is employed, it being neither of the latch needle nor spring beard needle type, but of the form shown in Patent 1,391,033, granted September 20, 1921.

The invention consists in the features and combination and arrangement of parts hereinafter described and particularly pointed out in the claims.

In the accompanying drawings Figure 1 is a sectional view of part of the cylinder and dial of a rib knitting machine embodying features of my invention. The hooked yarn drawing elements being partly advanced.

Figure 2 is a view similar to Figure 1 with the hooked yarn drawing elements and their quills or loop controlling elements in advanced position for receiving the yarn.

Figure 3 is a view similar to Figure 2 with the hooked yarn drawing elements in the same advanced positions of Figure 2 but with the quills partly retracted.

Figure 4 is a view similar to Figures 2 and 3 but with the hooked elements of the cylinder knitting instruments or units partly retracted and with the quills in the same position as in Figure 3.

Figure 5 is a view similar to Figures 1, 2, 3 and 4 but with old loop cast from the cylinder knitting instrument or unit and just before the new dial loop is taken by the hooked element of the dial knitting instrument.

Figure 6 shows the parts in a slightly different relative position from Figure 5, that is, the new dial loop has been taken by the hooked element of a dial knitting instrument or needle unit.

Figure 7 is a similar view with the dial hooked element retracted and the old dial loop cast off.

Figure 7a is a section of rib fabric.

Figures 8 and 9 are respectively a plan view and front view of a yarn feed device.

Figures 10 to 17 are sectional view of a rib machine employing sinkers and web holders.

Figure 18 is a sectional view of the needle cylinder and web holder bed.

Figure 19 is a sectional view of the web holder bed.

Figure 20 is a sectional view of the dial.

The needle unit or knitting instrument comprises a hooked yarn drawing element having a hook 2 and a stem 1 with a butt 3. 65 This element is slidably mounted in a quill or loop controlling element which is slidably mounted in one of the grooves of the cylinder or dial as the case may be. The quill is made up of a stem 4 of channel form receiving the stem of the hooked element, a nose 5, a rise 6; a swell or hump 7, a drop 8 and a throat 9, a butt 10, and there is a stop 11 fixed or riveted between the walls of the stem. 75

This knitting instrument or needle unit operates in forming the stitches like that of the application before described and the movements need not be followed out in detail at this point. It will be observed however that the knitting units have no latches or spring beads, and the use of all the devices attendant upon these old types of needles is avoided together with the various objections which exist thereto and which are well known to skilled knitters. 80

I employ in my rib machine web holders 12 which may act in the ordinary way when forming welts on the cylinder needle units. I use the web holders for an additional function for which they are formed with a preferably blunt nose as at 13. The web holder is so proportioned and is so operated that its blunt nose reaches nearly to the verge of the dial leaving space just enough for the 95 fabric to pass down between the web holder nose and the verge of the dial, and thus the dial loop will be held in a definite position on the quill stems as they are projected forward to receive new yarn. The loops will 100 lodge in the throats and will be held out of the path of travel of the cylinder instruments. This loop holding action of the web holder is illustrated in Figures 3, 4, 5, 6 and 7. Figure 2 represents the retracted position of the web holders. 105

Another feature of the present invention is a dial so constructed that the butts of the

needle units may be operative in the dial grooves nearer the verge or in a circle or path of a larger radius than heretofore.

It is well known in the art that dial 5 grooves that are radially arranged are thinner and weaker nearest to the center of the dial, and that there must be a considerable space left near the verge to enable the latches to swing freely, therefore the needle 10 grooves for the butts cannot extend into the zone of the swinging latch. Fineness of gauge in rib machines is limited to a degree by the thickness of the needle walls near the center of the dial. The herein described dial 15 has a larger needle wall radius due to the fact that latches are not used in the needles, therefore no free space is provided for them, also to the new form of dial which has a groove as channel 14 into which the 20 hooks of the elements 1 recede and draw loops, and the extended needle wall 15 reaching, if desired quite to the cylinder needle plane. Owing to the length of the wall greater thickness is obtained for strength 25 and cams for the needle units can be of lower angle than heretofore, and secure the same degree of recession of the needle unit in a given arc than cams of the usual angle set much nearer the center.

30 As shown in all the drawings the butts of the hooked elements of the needle units or knitting instruments are located, even when in retracted position, comparatively close to the verge of the dial and the butts 35 of the quills or loop controlling elements also lie comparatively close to the dial verge, and consequently a larger number of knitting units per inch can be provided than would be the case were it necessary to carry 40 the needle grooves to near the axial center of the dial.

The web holder bed is mounted on the cylinder near the needle verge. It is well known in knitting, that lint lodges, accumulates and packs, in the needle grooves or any other openings near the knitting point unless means are provided to clear the lint as fast as it lodges. The dial mounting construction herein disclosed is designed for the 50 specific purpose of avoiding lint accumulating or packing. The needle unit itself by its movement cleans the lint away at each stroke.

This mounting comprises the ledge 16 55 made up of outward extensions of the needle slot walls and upon the ledge the web holder bed 17' is supported being clamped thereto by the member 17 engaging the lower face of the ledge and held by a screw as 18 to the 60 under side of the web holder bed. .

Referring to the sinker fed rib machine:

The drawing Figures 10 to 17 show a rib knitting machine having two sets of needle units or knitting instruments arranged at 65 right angles to each other. Sinkers for feed-

ing yarn to the cylinder needles are shown, and the web holders are illustrated as loop or stitch guards for the dial loops during rib knitting, and fabric, or web holders when welts or flat fabric is being knitted during 70 which time the dial needles are inactive.

The sinkers and web holders may be of any desired form and operated in any suitable way. For convenience of illustration I 75 show sinkers and web holders of the interlocking type such for instance as are made the subject of Letters Patent of the United States, Feb. 5, 1918, No. 1255258.

This form is used as an example of any 80 form which may be suitable for the purpose. The sinker is shown at 19 operated by a cam 20 and having a projection 21 to engage shoulders 22, 23 on the web holder, and a spring band 24 which tends constantly to force the web holders inwardly towards the 85 center of the machine.

Figure 10 shows the normal, or temporarily idle position of sinkers, needle units, and web holders. At this period the hooked elements of the cylinder units are higher than their lowest, or stitch drawing position, and the cylinder quill is at, or about the lowest position of its travel. The quill point is below the cylinder verge out of possible contact with the yarn or fabric loops. The same 90 is true of the dial needle. The web holder is in its extreme advanced position, the nose contacting a dial loop, but not engaging cylinder loops because the yarn reaches from the cylinder needle units to the dial 100 needle units forming an inverted V and there is no yarn or fabric within reach of the throat of the web holder, during rib knitting. The sinker is in a position of rest, a little advanced from its extreme backward movement, so as to permit the spring bands 105 behind the web holder to push the said web holder against the dial loop.

Figure 11 shows the hooked element of the cylinder needle unit advanced nearly 110 or quite to its extreme upward movement preparatory to receiving yarn from the sinkers. The cylinder quill has advanced upward until the point has passed through the fabric loop on the stem of the hooked needle element. The sinker has retired backward so as to allow the thread carrier to pass the sinker nose, also to withdraw the web holder, and free any possible grip it may have on the fabric or dial loop so 115 that the fabric may be pulled taut by a weight or take-up. The dial needle units have not materially changed their position from Figure 10.

Figure 12 shows the sinker projected forward to sink yarn across the throat of the hooked element of the cylinder needle unit with the nose of the sinker and yarn in a position over the dial needle unit and projecting into the dial needle slot. The web 120

holder being released by the sinker is now in contact with the dial loop by reason of the spring band against the web holder heel stem. The hooked element of the dial needle 5 unit has advanced nearly as far as is safe without contacting the sinker which operates in the same radial plane therewith. The dial quill has not materially advanced. The cylinder quill has advanced nearly as 10 far as is safe to go without contacting the new sunk loop on the cylinder hooked element (side contact).

Figure 13 shows the sinker and web holder in practically unchanged position, 15 the dial hooked element slightly further advanced and the dial quill quite well advanced through the dial loop. The loop being restrained from advancing by reason of the web holder nose contacting it. The 20 cylinder quill having advanced until the swell is safely through the cylinder loop, and the cylinder hooked element has retracted until the hook is guarded by the swell of the quill. From this position the 25 hooked element and quill will travel together during the remainder of their downward movement.

Figure 14 shows the sinker retiring with the new loop ready to drop off the sinker 30 lip, the cylinder hooked element and quill having retired until the fabric loop is about to pass over the hook. The web holder position is unchanged. The dial hooked element has advanced to its extreme forward position, 35 and the dial quill has advanced until the dial loop is safely in the quill throat.

Figure 15 shows the dial quill slightly retracted but it still holds the dial loop in the quill throat, so as to allow the new 40 yarn to be drawn across the throat of the dial hooked element. The cylinder hooked element has moved downward, and has cast off its fabric loop and is shown pulling the new yarn across the dial hooked element. 45 This view shows the division of the fabric loop from the new fed yarn on the dial needle unit. This is an important feature of a rib machine. The sinker has still further retracted but not enough to act on or with- 50 draw the web holder.

Figure 16 shows the dial hooked element retracted so as to hold the newly fed yarn in the hook, the quill swell guarding the said hook.

55 *Figure 17.*—Between the position of Figure 16 and this figure, the cylinder hooked element and cylinder quill have retracted to their lowest position, the quill remaining there, and the said hooked element has advanced to relieve the strain on the yarn during the time while the dial hooked element has been casting off its old loop and has drawn the new loop through it in the manner common to rib machines. In this 60 figure both sets of needle units are about 65

to assume the positions shown in Figure 10, or normal position.

The hooked element is moved upward by a cam and downward by another cam, Figure 11. The quill is pushed upward by 70 a cam in a different cam path from that of the hooked element, and are pushed downward by another cam a part of the way, then the butt of the hooked element contacts the quill stop and the two travel together under the impulse of the needle cam acting on the butt of the hooked element. 75

Much latitude must be allowed in the matter of timing the relative movements of the hooked element and quill. The relative 80 movements may be varied according to the ideas of a knitter or machine designer without departing from the main purpose of this invention.

As before stated the walls of the needle 85 slots of the dial may be extended, see Figures 10 and 12, to the vertical plane of the backs of the hooked elements of the cylinder needle units, or they may extend only as far as the verge of the dial. In either 90 case the sinker throat and nose may enter the dial slot with safety because the slot is always wider than the sinker nose plus the space necessary to accommodate the yarn on each side of it, so that the yarn will not be 95 chafed. In the construction mentioned above with the wall of the dial slot extending to the vertical plane of the back of the cylinder hooked element the advantage is gained that the end of the needle slot 100 wall will present a support for the hooked element to resist the bending tendency due to the thrust of the sinkers against the yarn and through the yarn upon the hooked element. The hooked element may be of the 105 finest gauge on this account.

In the latch needle machines the above results cannot be attained because the latches bar the sinkers from entering the needle slot and consequently the walls of the dial 110 slots could not be carried forward to furnish supports for the backs of the hooked elements of the cylinder needle units.

Reverting to the hooked elements and quill member as embodied in a rib machine, it will be noted that the over-all thickness of the quill is equal to that of the usual spring needle of the same gauge or number of needles to the inch. The 115 hooked element sliding in the quill is of necessity thinner than the quill to the extent of the two walls of the quill. Therefore, the space between two hooked elements at the level of the sinkers is greater than in machines employing the ordinary forms of 120 latch or spring beard needles. This allows more space for the yarn and for the passage of lumps, bunches or knots, and there is less liability of imperfections occurring in the 125 fabric. The hooked element of my present 130

construction is more delicate than ordinary needles of the same gauge of machine but this is compensated for by the support afforded this hooked element by the extended 5 wall of the dial needle groove, and if this support is not provided then the back and sides of the quill afford supporting means, and this is so with or without the extended wall.

- 10 Referring to the action of the quill cams, it will be understood that these acting on the quill butts will force the quills forward and part of the way back. The last part of the quills inward or backward movement 15 is imparted to it by the butt of the hooked element contacting with the stop of the quill, and thereby the hook of said element and the swell of the quill will be brought into registry so that loops may pass freely over 20 the swell of the quill and the hook.

The hooked elements may travel forward to receive the yarn in advance of the quills movement and therefore low angled cams may be used against the quill butts.

- 25 A single row of hooked yarn drawing elements with their quills or loop controlling elements may be used together with a row of sinkers cooperating therewith and relatively fixed needle guards or supports for 30 resisting the thrust of the yarn when being sunk may be used with this single row of

needle units acting like the ends of the extended dial slot walls, above described.

I claim:—

1. A rib knitting mechanism comprising 35 two carriers, two rows of instruments for knitting rib fabric, each instrument having an inner element and a channeled element U shaped in cross section, embracing the inner element and in the same grooves therewith, the U shaped elements having throats to hold the two rows of loops definitely separated and instruments arranged opposite the verge of the carrier of one set of instruments to hold the loops to said 40 verge against the thrust of the said channeled elements to lodge the said loops in the throats thereof.

2. A rib knitting mechanism comprising 45 cylinder and dial carriers, a row of instruments for each of said carriers cooperating to knit ribbed fabric, said instruments having throats to hold the two rows of loops definitely separated and instruments arranged opposite the verge of said dial to 50 hold the loops on said dial instruments to said verge against the thrust of said dial instruments to lodge the said loops in the throats thereof.

In testimony whereof, I affix my signature. 55

J. FRANK WILCOMB.
